UNITED STATES PATENT OFFICE.

WILLIAM O. DUNTLEY, OF ST. LOUIS, MISSOURI.

INSULATING-JOINT.

SPECIFICATION forming part of Letters Patent No. 553,844, dated February 4, 1896.

Application filed March 25, 1895. Serial No. 543,177. (No model.)

To all whom it may concern:

Be it known that I, WILLIAM O. DUNTLEY, residing at the city of St. Louis, State of Missouri, have invented a new and useful Improvement in Insulating-Joints for Electric or Combination Fixtures, of which the following is a description, reference being had to the accompanying drawings, forming part of this specification.

10 My invention relates to that class of insulating-joints adapted to be secured to the gas-pipe, and to attach thereto a fixture which will be effectively insulated from the said gas-pipe.

15 The object of my invention is to provide a joint that will be compact in form, that can be taken apart, and that will afford perfect insulation.

20 My device possesses features of novelty hereinafter specifically pointed out and claimed.

Referring to the drawings, Figure I illustrates a side elevation of the device. Fig. II illustrates a vertical section through the line 25 II II of Fig. I. Fig. III illustrates a bottom view of the upper section, 2. Fig. IV illustrates a top view of the lower section, 4. Fig. V illustrates a side elevation of the glass interior insulator and the surrounding fibrous 30 insulator-washer.

1 represents the gas-pipe, which projects through the ceiling or wall. 2 is the upper section of the insulator screwed to said gas-pipe 1.

35 3 is a hollow cone, attached to the bottom of the part 2.

4 is the lower section of the insulator.

5 is a collar, fitting over the shoulder of section 2 and screwing onto section 4.

40 6 is the gas-pipe to the chandelier or other fixture.

7 is an insulating-washer, composed of fibrous material, placed between the collar 5 and the sections 2 and 4. 8 is a second insulating-washer, also of fibrous material, placed 45 between the two sections.

9 is a glass interior insulator, provided with a central hollow projection, 10, at its bottom of less external diameter than the surrounding portion of the lower insulator-section, 4.

50 11 are ridges or lugs cast in the bottom of section 2, and adapted to bear against and

sink into the upper side of the fibrous insulating-washer 8. 12 are like ridges or lugs, cast on section 4 adapted to sink into the lower part of said washer 8.

13 is a mica washer, placed between the upper section, 2, and the collar 5.

An especial feature of my invention is the interior glass insulator 9. This insulator has 60 a flat top bearing against the flat bottom of the upper section, 2, and a flat bottom bearing against the flat shoulders of lower section, 4. It is perforated through the center, and into said perforation projects the cone 3 at the bottom of the upper section, 2. While at the bottom of the insulator 9 the cone 10 extends said perforation and conducts moisture out into pipe 6. These two cones together prevent the accumulation in the insulator-joint 70 of moisture precipitated along the gas-pipe and draining toward the gas-fixture.

The bearing and strain are borne by the washers 7 and 8 into which the lugs 11 and 12 press. As the parts are bound together by 75 screwing the collar 5 onto the section 4, the sections 2 and 4 are brought into contact with the flat top and bottom of insulator 9. This prevents the glass insulator from breaking, yet furnishes a perfect insulation. The parts 80 are made gas-tight by previously painting them with a proper preparation for that purpose.

The moisture which condenses in all gas-pipes drips through the cone 3, through the 85 perforation of the insulator 9, through the cone 10 and into pipe 6. The glass insulator 10 prevents it from coming in contact with the fibrous washers and being absorbed thereby, and thus completing a connection between the two sections. This filling of the 90 space between the two sections by a glass insulator of the form described is of special advantage when gasoline gas is used, because the incline necessary to drain back to the reservoir would, in ordinary constructions, allow moisture to come in contact with the fibrous washers, an evil which is avoided by my device. The use of glass as an insulator 95 is of further advantage, as no gas can eat through it. This joint screws onto the gas-pipe from the insulator and not from the collar. It is impossible, therefore, to get a ground-circuit by a contact with the joint.

While I have described washers 7 and 8 as composed of fibrous material, I do not limit myself to this construction, as it is evident any other suitable material may be used.

5 I claim as my invention and desire to secure by Letters Patent—

1. In an insulating-joint, the combination of a section adapted to be secured to the gas-pipe, a cone 3 at the lower end of the perforation therethrough, a second section insulated from said first section, a collar 5 to secure said two sections but in contact only with said second section insulator 13, interior glass insulator 9, having a drip-cone at the bottom of 15 the perforation therethrough, and fibrous in-

sulating-washers adapted to bear the strain of the parts, substantially as and for the purposes set forth.

2. In an insulating pipe-joint, the combination of the upper and lower attaching parts 20 and the interposed insulator said upper part having a drip-cone for delivering water of precipitation into the insulator, and said insulator having a drip-cone for directing said water past the lower attaching part, as explained.

WM. O. DUNTLEY.

In presence of—

CHRIS MUELLER,
STANLEY STOVER.
